UNITED STATES PATENT OFFICE.

NATHAN ROYACK, OF BROOKLYN, NEW YORK.

DOOR-OPENING DEVICE.

1,204,072.

Specification of Letters Patent.

Patented Nov. 7, 1916.

Application filed October 10, 1914. Serial No. 866,123.

To all whom it may concern:

Be it known that I, NATHAN ROYACK, a subject of the Czar of Russia, and resident of Brooklyn, in the county of Kings and State of New York, have invented certain new and useful Improvements in Door-Opening Devices, of which the following is a specification.

The invention relates to improvements in door-opening devices, adapted more particularly as an emergency exit door leading from a public hall or assembly room, for affording rapid egress to the assembled persons; and the object of the invention is to provide a simple and effective self-opening door, arranged to be actuated by the ordinary step of an approaching person; and the invention further includes certain details of construction hereinafter set forth.

In describing the invention in detail reference is had to the accompanying drawings, forming a part of this specification, and wherein like characters of reference are used to designate like parts throughout the several views, and in which:

Figure 1 illustrates a side elevation of a door-frame and door arranged with the opening device embodied in the present invention; Fig. 2 is a horizontal sectional view through the door-frame, showing the upper edge view of the door; and Fig. 3 is a vertical sectional view through the door-frame, showing a side edge view of the door.

In the drawings, numeral 1 designates a door, hingedly mounted to the door-frame 2 by the spring-hinges 3, the latter normally acting to open the door outwardly, as indicated by the dotted lines. Mounted upon the door is a latch-plate 4, of common construction, provided with the spring-projected latch-bolt 5, actuated through the usual stem by the handle 6, disposed on the interior side of the door. Upon the frame is fixed a socket-plate 7, adapted to receive the latch-bolt and hold the door in a closed position against the action of the spring-hinges 3. Fixed to the latch-spindle on the interior side of the door, is an actuating arm 8, to which is pivotally jointed a connecting-rod 9, having at its lower end suitable supporting-lugs for the rotative support of the roller 10. The connection-rod is positioned upon the door and guided for vertical movement by the screw or stud 11, the latter passing through a slot 12 in the rod and secured to the door proper.

Mounted in the floor adjacent the door is a movable foot-plate 13, pivotally supported at one end by the pin 14 and yieldingly supported at the opposite end by the spring 15. At its upper surface the foot-plate is normally positioned on a level with the floor line 16, and is further provided with a projecting pin 17, adapted to engage the upper surface of the roller 10.

In operation, the free end of the foot-plate 13 is depressed by the weight of the person approaching the door, which movement causes the engagement of the pin 17 with the roller 10, serving to depress the latter and its connected rod 9 for effecting the movement of the actuating arm 8 and the retraction of the latch-bolt 5, thereby permitting the door to open outwardly by the action of the spring-hinges 3. The closing movement of the door may be effected from either side of the doorway while the foot-plate is in its normal upper position, and during this closing movement the exterior beveled section of the latch-bolt 5 engages the socket-plate 7, causing the bolt to be retracted and the descent of the arm 8 and the rod 9, the latter movement being influenced by gravity and acting to position the connected roller 10 below the pin 17, fixed upon the foot-plate, the relative arrangement being such as to allow a free lateral movement of the roller along the pin.

To prevent the premature operation of the door, guardrails 18 may be disposed on opposite sides of the doorway, as shown.

As thus arranged it will be evident that the door in its opening movement may be operated from the inside only, and that the movement may be effected without special act or attention on the part of the persons passing therethrough.

What I claim as my invention and desire to secure by Letters Patent, is:

1. In combination, a door-frame, a door mounted in said frame, a spring-projected latch mounted on the door and arranged for locking engagement with the frame, a rod vertically movable on the door and connected at its upper end to said latch for the release thereof, a roller mounted at the lower end of said vertically-movable rod, a foot-plate yieldingly supported for vertical movement in the floor adjacent said door and normally held in upper position and adapted to be depressed by the action of the foot, and a pin fixed to said foot plate and

adapted when the door is closed to engage said roller and downwardly urge said rod for the release of said latch.

2. In combination, a door-frame, a door mounted in said frame, a spring-projected latch mounted on the door and arranged for locking engagement with the frame, means normally acting to automatically open said door when the latter is unlatched, a rod vertically movable on the door and connected at its upper end to said latch for the release thereof, a roller mounted at the lower end of said vertically-movable rod, a foot-plate yieldingly supported for vertical

movement in the floor adjacent said door 15 and normally held in upper position and adapted to be depressed by the action of the foot, and a pin fixed to said foot plate and adapted when the door is closed to engage said roller and downwardly urge said rod 20 for the release of said latch.

Signed at New York, in the county of New York and State of New York, this eighth day of October, A. D. 1914.

NATHAN ROYACK.
